ABSTRACT

The invention relates to fluid pressure motors and pumps of the type having a gerotor displacement mechanism and an axial type of valve. The casing has inlet and outlet ports and a speed and load control port. The rotary valve has first and second sets of alternately arranged passages with one set having the usual constant fluid communication with the casing outlet port. The other set of valve passages includes some passages in constant fluid communication with the casing inlet port and at least one passage in constant fluid communication with the casing control port. A change over unit has a fluid supply inlet, a fluid exhaust outlet and a control outlet connected to the casing control port referred to above. The change over unit has means for selectively and alternately connecting the control port to the supply inlet and exhaust outlet thereof.

MESHING ROTARY PISTON MACHINE WITH AN INTERNAL SHAFT

The invention relates to a fluid pressure motor or pump with a change over control unit. The apparatus includes a meshing rotary piston machine, especially an engine, with an internal shaft, comprising two toothed elements, namely a toothed wheel and a toothed ring, having one more tooth than the wheel, which between them form displacement chambers, and further comprising a rotary distributing valve, a first part of which is connected to and rotates with the first toothed element and contains valve openings leading to the displacement chambers, the number of which openings is equal to the number of teeth on this toothed element, and a second part of which is connected to and rotates with the second toothed element and contains valve openings connected respectively to a pressure side first union and to a low pressure of intake side second union, the number of these openings being equal to twice the number of teeth on this toothed element.

In one known machine of this kind the toothed elements not only act as rotary pistons but also effect a reduction. Machines of this kind are therefore particularly well suited for slow operation. Engines have a high torque and pumps have high delivery capacities.

The objects of the present invention is to provide a rotary piston machine of the initially stated kind which has more than one transmission ratio.

According to the invention, this object is achieved by the use of a second toothed element having an even number of teeth and by the provision of a change over device by means of which each second or each fourth of the valve openings in the second part of the distributing valve is optionally connectable to one of the unions, preferably the pressure side first union, and the intermediate valve openings are connectable to the other union.

When each second opening is connected to the same union, the machine operates in the normal manner. If however, only each fourth valve opening is connected to one of the unions whilst the three intermediate valve openings are assigned to the other union, a new kind of operation is surprisingly achieved. If an engine is operated under constant external conditions (pressure-level and throughput), then it operates at approximately twice the speed and with half of the torque. The transmission varies in the ratio 1 : 2. If the machine in question is a vehicle engine, its speed can be changed without the aid of a change over gear. The same applies in the operation of a pump.

It is particularly advantageous if the toothed wheel constitutes the second toothed element and has six teeth. With this arrangement, only one chamber is connected to the pressure side each time. This chamber is located in the middle of the three otherwise effective pressure chambers, so that the chamber having the greatest effective component influences the rotation of the toothed wheel. The same applies when this one chamber is connected to the low-pressure or intake side.

A simple construction is that in which each fourth valve opening in the second part of the distributing valve is continuously connected to one of the unions and the valve openings on each side of each said fourth opening are continuously connected to the other union, and in which the change over device only connects the remaining valve openings, as required, to one or other

of the unions. In this arrangement, only each fourth valve opening requires to be changed over.

In a preferred embodiment the valve openings in the second part of the distributing valve take the form of axial grooves in the periphery of a rotary slide, three axially staggered annular grooves are formed in the periphery of the rotary slide, the first of these being connected to one of the unions and being located on one side of the axial grooves, the second being connected to the other union and being located on the other side of the axial grooves and the third being connected to the change over device and being located on that side of the second annular groove remote from the axial grooves, and each fourth axial groove joins the first annular groove, and the axial grooves on each side of each said fourth axial groove joins the second annular groove, whilst bores in the rotary slide connect the remaining axial grooves with the third annular groove. Since only each fourth axial groove has to be connected to the third annular groove, the bores required for this can be comfortably provided in the rotary slide. With a distributing valve of this kind, it is also possible to reverse the direction of rotation by transposing the first and second unions.

The change over device may be manually actuated. It may however also be operated automatically. For this purpose, the change over device is preferably constituted by a three-way valve which is actuated in dependence upon the drop in pressure in the machine. If the pressure drop in an engine is reduced as a result of a decrease in load, the engine automatically switches over to another kind of operation which permits a higher speed with lower torque, and vice versa.

In this connexion, it is particularly advantageous if the three-way valve has a plunger which in a first position connects a pressure passage, and in the second position, a low-pressure passage to the change over valve openings, and which can be moved from one of its positions to the other in dependence upon the pressure in a pressure chamber adjacent an end face of the valve, from which chamber the piston can be displaced into its other position, and if the pressure-chamber is connectable to the first or second union by way of a control valve and in dependence upon the position of a piston displaceable by the pressure drop in the machine, this piston overriding the associated valve openings with a lost motion action. As a result of the lost motion, an upper pressure limit is established at which the engine is switched to normal speed from high speed, and a lower pressure limit established at which the engine is switched from normal speed to high speed.

In the above-described arrangement it is also possible to fit the control valve in the interior of the plunger of the three-way valve.

The invention will now be described in greater detail by reference to an embodiment illustrated in the drawing, in which:

FIG. 1 is a diagrammatic illustration of the construction of the machine of the invention together with the change-over device,

FIG. 2 is a longitudinal section through the operating part of a machine in accordance with the invention,

FIG. 3 is a developed view of the periphery of the rotary slide seen in FIG. 2,

FIG. 4 is a longitudinal section through the change over device of the machine of the invention, and

FIG. 5 contains two graphs showing how the change over operation is dependent upon pressure.

For the purpose of the following description, it is assumed that the machine of the invention is operated as an engine. A pipe supplying pressurized fluid is therefore connected to a first union 1, and a discharge pipe to a second union 2. The engine includes a toothed ring 3 (the first toothed element) having seven teeth, and a toothed wheel 4 having six teeth. Displacement chambers 5 are formed between the ring and the wheel.

A distributing valve 6 consists of a first part 7 connected to and rotating with the toothed ring 3, and a second part 8 connected to and rotating with the toothed wheel 4. The valve-part 7 contains seven valve openings 9 which are evenly spaced around its periphery and each of which is connectible by a passage 10 to a displacement chamber 5. The second valve part 8 contains twelve openings 11 which are divided into three groups a, b and c. Each fourth opening a is continuously connected through pipes 12 to the pressure side first union 1. The second group b consists of openings on either side of the openings 11a. The valve openings 11b are continuously connected through pipes 13 to the second union 2. The third group c is formed by the remaining openings which are connected through pipes 14 to a change over device 15. This change over device can occupy either of two positions. In the first position, openings of the group c are connected to the first union 1. In the second position openings of the group c are connected to the second union 2. The change-over device is actuated by way of a pulse line 16 in dependence upon the pressure-drop in the engine.

In the position of the change over device as illustrated, the valve openings 11c are connected on the pressure side. They then act in the same manner as the valve openings 11a. This results in a machine of this kind operating in the normal way. If however the change over device 15 is moved into its other position, only the valve openings 11a are located on the pressure side, whereas all the other valve openings are connected to the discharge side. Then, only the discharge chamber 5a, indicated by hatching in FIG. 1, is supplied with pressurized fluid. The instantaneous point of rotation M of the toothed wheel 4 is near the top tooth. The fluid pressure obtaining in the chamber 5a therefore applies to the toothed wheel 4 a force that is substantially at right angles to the lever-arm that rotates the toothed wheel. Therefore, in contrast to what would be the case with pressurized fluid in the neighbouring chambers, the fluid in chamber 5a is effective with full force for the moment of rotation. Irrespective of the particular position of the toothed wheel 4 and of part 8 of the distributing valve, there is always only one displacement chamber 5a, filled with pressurized medium, present. This displacement chamber 5a also always occupies approximately the same position in relation to the instantaneous point of rotation M of the toothed wheel. Tests have shown that in a control system of this kind the torque is approximately halved and the speed is raised to approximately twice the value. Efficiency, which is normally 80 percent in a toothed wheel machine of this kind, only drops to approximately 75 percent. The degree of irregularity rises from 4 percent to only approximately 10 percent. This is due to the fact that the single effective chamber 5a undergoes the greatest change in volume for a given extent

of rotation of the toothed wheel, whereas the two adjacent chambers only change slightly.

It is clear that similar conditions will occur if the unions 1 and 2 are transposed. Then, only one chamber is connected to the discharge pipe, whereas the other displacement chambers connected to the pressure side partially cancel each other out as regards their effect.

A practical arrangement is illustrated in FIGS. 2 to 4.

The working part of the machine, which is illustrated in FIG. 2, has a housing 17 which is closed at the left-hand end by a cover plate 18, and at the other end is extended by a spacer 19, the toothed ring 3 and the cover plate 20. The various parts are interconnected by means of screw bolts 21. A main shaft 22, integral with the rotary slide 23, rotates in the housing. The main shaft is connected to the toothed wheel 4 by a universal joint shaft 24. For this purpose the universal-joint shaft 24 has toothed heads which mesh with corresponding internal teeth in the main shaft 22 and the toothed wheel 4.

The housing 17 constitutes the first part 7, and the rotary shaft 23 the second part 8 of the distributing valve 6. The valve openings 9, which are connectible to the displacement chambers 5 through the bored passages 10 in the housing 17 and in the spacer 19, are therefore provided at the inner periphery of a bore in the housing. The valve openings 11, in the form of axial grooves, are formed on the periphery of the rotary slide. A first annular groove 25 is located to the right of the axial grooves 11 and is connected to a pipe 26. A second annular groove 27 is located to the left of the axial grooves 11 and is connected to a pipe 28. A third annular groove 29 is provided at that side of the second annular groove 27 remote from the axial grooves 11, and is connected to a pipe 30. Bores 31 lead from the annular groove 29 to the axial grooves 11 of group c. As shown in FIG. 3, the axial grooves 11 of group a are extended to the annular groove 25, whereas the axial grooves 11 of group b are extended to the annular groove 27. The axial grooves 11 of group c are spaced from the two annular grooves 25 and 27, and only communicate with the annular groove 29.

FIGS. 2 and 4 together illustrate a complete machine. FIG. 4 illustrates a form of the change-over device 15. This device has an outer casing 32 in which is inserted a sleeve 33 held at each of its ends by a plug 34 and 35. The sleeve accommodates a displaceable plunger 36, in which a groove 37 enables an outlet opening 38, connected to the pipe 14, to be selectively connected to an inlet chamber 39 or an inlet chamber 40. The inlet chamber 39 is connected to the pipes 12 and 13 by way of a pipe 41 and non-return valves 42 and 43 respectively which open towards the chamber 39. The higher pressure therefore always obtains in the inlet chamber 39 irrespective of whether the pressurized medium is supplied through the union 1 or the union 2. The inlet chamber 40 is connected to the pipes 12 and 13 by way of a pipe 44 and two non return valves 45 and 46 respectively which close towards the inlet chamber 40. The discharge pressure therefore always obtains in the inlet chamber 40, irrespective of whether the discharge pipe is connected to the union 1 or the union 2. A chamber 47 containing a compression spring 48 is provided at one of the ends of the plunger 36. The chamber 47 is connected to the pipe 44 and is therefore under discharge pressure. At the opposite end of the plunger 36 is a pressure chamber 49 to which the sup-

ply pressure or the discharge pressure can be optionally admitted through a passage 50 incorporating two valve openings 51 and 52. For this purpose there is provided a control piston 53 which is displaceable in a bore of the plunger 36, thereby overcoming the force of a spring 54. The bore is sealed by means of a resilient plug 55. The supply pressure obtains in the chamber 56 as a result of its communicating with the pipe 41 by way of the pipe 57, and the discharge pressure obtains in the chamber 58 since it communicates with the inlet chamber 40. The piston 53 undergoes lost motion relatively to the valve openings 51 and 52, so that when the piston is displaced, one opening is only uncovered after the other has been closed for some time.

This construction of change over valve leads to an automatic change in speed during which the two working ranges overlap each other. In the upper graph in FIG. 5, pressure is plotted against time, whereas in the lower graph engine speed is plotted against time. If it is assumed that the engine is initially running at high speed and the change over valve is in the position illustrated in FIG. 4, then as soon as the predetermined pressure difference P_1 is established, the control piston is pushed so far to the left that the valve opening 52 is uncovered, and supply pressure is admitted to the pressure chamber 49. The valve plunger 36 and thus the change over device 15 therefore move into the other end position. The engine then runs at the lower speed n_1 . The drop in pressure diminishes to a corresponding extent. If, upon further loading of the engine, the pressure rises above the limit value P_1 , the conditions do not change. Loading can be continued up to the safety pressure P_3 . This safety pressure is set by means of a safety valve, not illustrated. If the load now drops, the conditions remain unchanged until the pressure drop falls below the level P_2 . During the fall in pressure the valve opening 52 will have been initially closed by the control piston 53, so that there is no change in the conditions; some time later the valve opening 51 is uncovered, so that the pressurized fluid can escape from the pressure chamber 49 towards the discharge side, since the plunger 36 is pressed to the right by the spring 48. The engine then runs again at the initial speed n_2 . This speed is maintained even if the drop in pressure falls below the value P_2 . Thus, the engine runs at normal speed within the pressure range A, and at high speed within the pressure range B, these two ranges overlapping each other.

If the pipes connected to the unions 1 and 2 are transposed for the purpose of reversing the direction of rotation, there is no change in the change-over device 15,

because of the presence of the non-return valves 42, 43, 45 and 46. Instead a change over still occurs when the predetermined differences in pressure are exceeded.

5 I claim:

1. Fluid pressure apparatus comprising a casing having inlet and outlet ports, said casing having a speed and load control port, chamber forming means for forming expanding and contracting chambers, a valve having a first part with channels extending to said chambers, said valve having a continuously rotatable second part with first and second sets of alternately arranged passages, said first set of passages including some passages in constant fluid communication with said inlet port and at least one passage in constant fluid communication with said control port, said second set of passages being in constant fluid communication with said outlet port said control port being in selective communication with either the inlet or outlet port.

15 2. Fluid pressure apparatus according to claim 1 wherein said second valve part is cylindrically shaped and has three axially spaced annular channels for said first and second sets of passages, said annular channels being respectively in constant fluid communication with said inlet and outlet ports and said control port.

20 3. Fluid pressure apparatus according to claim 1 including a change over unit having a fluid supply inlet and a fluid exhaust outlet, said unit having a control outlet connected to said control port, said unit having means for selectively and alternately connecting said control port to said supply inlet and said exhaust outlet.

25 4. Fluid pressure apparatus according to claim 3 wherein said change over unit is actuated in response to a pressure drop change across said inlet and outlet ports.

30 5. Fluid pressure apparatus according to claim 1 wherein said chamber forming means includes an internally toothed ring member and a cooperating externally toothed star member having fewer teeth than said ring member and being disposed eccentrically relative thereto.

35 6. Fluid pressure apparatus according to claim 5 wherein said star member has an even number of teeth and the alternate ones of said first set of valve passages are connected to said control port.

40 7. Fluid pressure apparatus according to claim 6 wherein said star member has six teeth.

45 8. Fluid pressure apparatus according to claim 7 wherein every forth one of said sets of passages is connected to said control port.
